UNITED STATES PATENT OFFICE.

HENRY J. JACOBS, OF BUFFALO, NEW YORK, ASSIGNOR TO BUFFALO LOUNGE CO., OF BUFFALO, NEW YORK, A CORPORATION OF NEW YORK.

TUFTING APPARATUS.

No. 830,504.

Specification of Letters Patent.

Patented Sept. 11, 1906.

Application filed December 4, 1905. Serial No. 290,152.

To all whom it may concern:

Be it known that I, HENRY J. JACOBS, a citizen of the United States, residing at Buffalo, in the county of Erie and State of New York, have invented a new and useful Improvement in Tufting-Machines, of which the following is a specification.

This invention relates to improvements in tufting-machines employing a moldboard from which rises a series of button holding or receiving posts over which the material forming the cover of the upholstering is designed to be arranged previous to the application of the filling material.

My invention has for its main objects the provision of a convenient means in the form of a measuring or gaging frame for enabling the operator to accurately, evenly, and rapidly lay out the filling material whereby a uniformity of firmness of tufts results, also in the provision of a convenient means for withdrawing such gaging-frame from the filling, leaving the latter within the tufts previous to the placing of the usual lining or backing over the mass and tufting-buttons.

Other objects and advantages of the invention will hereinafter appear, and the novel features thereof will be particularly pointed out in the claims.

Referring to the drawings, Figure 1 is an elevation and partial section of a tufting apparatus or machine embodying my improvements. Fig. 2 is a plan view of a portion of the measuring or gaging frame. Fig. 3 is a similar view of one end of the moldboard.

Similar numerals of reference indicate similar parts in all the figures of the drawings.

In carrying my invention into practice I employ the usual button-post supporting moldboard 1, which is oblong and of a size sufficiently large to accommodate and form the largest piece of upholstering that may be desired. This moldboard, as is usual, rests removably upon suitable supports 2 and may be provided upon its under side with cross-cleats abutting against the supports 2, whereby the relative position of the parts may be maintained. The moldboard is in the present instance provided at each of its four corners with a vertically-disposed angular guide 4 and at regular intervals with the usual vertically-disposed posts 5, between which occurs the cavities or molds 3. These posts are for the purpose of holding the usual

style of tufting-button 6, and for that purpose each is provided at its upper end with a button holder or socket 7.

Suspended movably above and in line with the structure thus described is a follower-board 8, the vertical movement of the board being secured by suitable suspension devices—as, for instance, a pair of ropes 9. These ropes may be counterbalanced at their opposite ends by weights and between the same pass over suitable sheaves or pulleys, the weights and pulleys not being shown.

From the under side of the aforesaid follower-board there depends a series of short plungers 10, preferably angular in cross-section and agreeing in number with the spaces 11 or molds occurring between the posts 5.

Between the follower-board and the moldboard, and preferably suspended from branch ropes 11, that are connected to the ropes 9 above the follower-board, is the "measuring" 75 or "gage frame" 12, so called by reason of the fact that its depth indicates the thickness of the filling. This frame in the present instance comprises opposite longitudinal sides and transverse end pieces (designated as 13 and 14, respectively) and a series of thin sheet-metal strips 15, which are supported by the side and end pieces and which at intervals are angularly disposed in alternately-opposite or reverse directions, the strips contact- 85 ing at their angles, thus producing a frame which consists of alternately large and small spaces 16 and 17, respectively. The larger spaces correspond in number with the tufts to be formed, while the smaller spaces occur- 90 ring at the angles of the larger spaces correspond with the number of button-posts 5. The two outer metal strips 15 of the series may be secured to the side and end pieces in any manner desired; but in the present in- 95 stance they are at intervals let into openings 18, formed in the side pieces, for which purpose the two outer strips are at intervals abruptly bent or kinked upon themselves, as at 19. The ends of each pair of strips are 100 brought together face to face, as at 24, and may be secured by wire bridles 20 or other- wise to the end pieces of the frame.

It will of course be appreciated that the invention is not limited to such details, as any construction of frame may be substituted for that shown, the only essential being that the frame comprise large and small openings ar-

ranged in the manner described—that is, with such openings alternating throughout the frame, the large openings corresponding with the position and size of the molds and 5 the smaller openings corresponding in number and location with the posts 5.

The side pieces 13 are in this instance provided each with a pair of hooks 21, to which are removably engaged the lower ends of the 10 branch ropes 11. The end pieces 14 may be provided with hooks 22, designed to removably engage with corresponding eyes 23, located at the ends of the moldboard 1.

This completes the construction, and the 15 operation of the apparatus is as follows: The material 25 to form the cover of the upholstering is by any suitable process first marked off into diamonds or squares, according to the style of tuft desired, and the points where the 20 button-shanks are to penetrate are thus indicated. The buttons are now placed in position in the button-holders with the piercing ends of the buttons extending upwardly. The material 25 is then arranged upon the mold- 25 board, being forced over the penetrating-points of the buttons, whereby, as is well known, the said cover is caused to sag between the buttons and into the molds 3. The gage-frame is now disconnected from the 30 branch ropes 11 and lowered upon the material 25. It will be observed that the side and end pieces of the gage-frame terminate short of what would be the corners of the frame, so that said side and end pieces take between 35 the angular guides 4 of the moldboard, or, in other words, within the spaces formed by said guides. When thus positioned, the larger openings 16 of said gage-frame register with the molds of the board 1, while the 40 smaller openings 17 of said frame receive the upwardly-disposed shanks of the buttons. The frame is now securely fastened in position by any suitable means—such, for instance, as the hooks and eyes 22 and 23.

45 Heretofore it has been necessary in applying the filling for the upholsterer to pack or fill each tuft by hand, experience and judgment being relied upon for a knowledge of how much filling to place in each tuft. The 50 result was that having no guide except the sense of feeling some tufts would receive more or a less quantity of filling than others, so that the desired uniformity of firmness of the tufts did not exist in the finished upholstery. 55 The operation of filling in accordance with my invention is, however, greatly simplified, facilitated, and accurate. Taking the parts in the position which we left them—that is, with the gage-frame 12 occupying the position shown by dotted lines, Fig. 1—it will be 60 apparent that the same presents to the upholsterer a series of compartments of uniform depth, so that all the upholsterer has to do is to completely fill each of such compartments 16, the filling when the operation is

completed presenting a level surface and of uniform depth and density. It will be observed that no nicety of judgment is required, but simply that each compartment be filled to a point about level with the upper edge of the gage-frame, so that what has heretofore required skill and judgment can be carried on by comparatively unskilled labor. When this has been accomplished, the follower-board is lowered, so that its plungers 70 10 enter the compartments 16 of the gage-frame. This is assured by means of the four guides 4 at the corners of the moldboard, the follower-board entering the same. The hooks 22 are now disconnected from the eyes 23 of the moldboard, and the branch ropes 11 are connected to the hooks 21 of the gage-frame. The outer ends of the ropes 9 are now drawn down or the gage-frame elevated by hand, which causes the plungers 10 to force the filling material outwardly from the various compartments 16, and as the gage-frame and follower-board rise to a point above said filling material will be left within the cover 25 at the points where the tufts are to be formed, 80 85 or, in other words, within the molds.

The remainder of the operation of forming the upholstering is the same as now commonly practiced in the art—that is to say, the usual backing (commonly of canvas) is 90 placed over the points of the buttons, a board having openings corresponding to the button-shanks is placed upon the backing, and the moldboard containing the parts thus arranged is transferred from the supports 22 95 to the press. Pressure being brought to bear through the medium of the press, the points of the buttons are forced upwardly through the backing and through the holes of the presser-board, and while the mass is in this 100 compressed condition the upholsterer with a suitable tool clenches the shanks of the buttons. The upholstering is now completed and may be removed from the moldboard.

Having thus described my invention, what 110 I claim as new, and desire to secure by Letters Patent, is—

1. In a tufting apparatus, the combination with a moldboard having guides at its four corners and producing intermediate side and end spaces, of a gage-frame comprising side and end bars terminating short of the corners of the frame and adapted to fit between said guides or within the spaces produced thereby.

2. In a tufting apparatus, the combination with a moldboard having upwardly-disposed button-posts, of a gage-frame removably supported upon said posts and having openings corresponding to the posts and to the molds in the board, and means for removably locking 125 the frame in position upon the posts.

3. In a tufting apparatus, the combination with a moldboard, of a gage-frame mounted thereon for gaging the depth of the filling material, and means for forcing said filling 130

material from said gage-frame and for raising said means and gage-frame free from the filling and moldboard.

4. In a tufting apparatus, the combination 5 with a moldboard, of a gage-frame having openings corresponding with the molds in the board, and a follower-board having plungers for entering said openings and forcing the filling material therefrom and means for attaching 10 the follower-board and gage-frame together and for simultaneously raising the two.

5. In a tufting apparatus, the combination 15 with a moldboard having button-posts, of a gage-frame comprising an external frame and a series of pairs of strips angularly disposed in alternately opposite directions to produce alternating large and small spaces corresponding with the molds and button-posts, 20 respectively.

6. In a tufting apparatus, the combination 25 with a moldboard having button-posts, of a removable gage-frame therefor, said gage-frame comprising side and end pieces and a series of pairs of strips disposed alternately at opposite angles thereby producing large and small openings corresponding to the molds and button-posts, respectively, said outer strips of the series being bent upon 30 themselves at intervals and let into openings formed in the side pieces of the frame and the ends of the strips connected to the end pieces of the frame, and means for retaining the frame upon the moldboard.

35 7. In a tufting apparatus, the combination 40 with a moldboard, of a gage-frame having openings corresponding with the molds in the board, a superimposed follower-board having plungers for entering the openings in the frame, suspension-ropes connected to the follower-board, and branch ropes leading from

the suspension-ropes and removably connected to the frame.

8. In a tufting apparatus, the combination 45 with a moldboard having angular guides at its four corners, of a gage-frame having side and end bars terminating short of the corners of the same and adapted to fit between the guides said frame comprising openings corresponding to the molds and button-posts in 50 the moldboard, a follower-board having plungers depending therefrom and corresponding to those openings in the frame, opposite the molds thereof said follower-board being adapted to fit within and be guided by the 55 angular guides of the moldboard, and a common suspension means for the follower-board and the gage-frame.

9. In a tufting apparatus, the combination 60 with a moldboard, of a gage-frame mounted thereon for gaging the depth of the filling material, and means for forcing said filling material from said gage-frame, and subsequently for simultaneously raising said means and gage-frame free from the filling and 65 moldboard.

10. In a tufting apparatus, the combination 70 with a moldboard having button-posts, of a gage-frame comprising a series of strips arranged to form spaces agreeing with the molds of the board and with the posts thereof, the walls of the latter openings being adapted to rest upon the posts, whereby said posts support the frame.

In testimony whereof I have signed my 75 name to this specification in the presence of two subscribing witnesses.

HENRY J. JACOBS.
